SEWING MACHINE

Howland F. Briggs, Buffalo, and Robert N. Cundall, Lackawanna, N. Y., assignors to Consolidated Packaging Machinery Corporation, Buffalo, N. Y., a corporation of New York

Application September 14, 1933, Serial No. 689,400

3 Claims. (Cl. 112—215)

Our invention relates to sewing machines, particularly sewing machines such as are adapted for heavy duty. The primary purpose for which these heavy duty sewing machines are designed is the sewing of heavy multi-ply paper bags such as are used for packaging cement and similar materials. These bags frequently consist of four or five plies of heavy kraft paper and are often gusseted so that the needle must traverse as many as twenty plies of paper. The weight of such a package is frequently very great so that a sturdy machine is necessary to close their open mouths.

We have found that previous sewing machines operated satisfactorily on cloth bags even with slight inaccuracies of feeding movement, because of the relatively flexible character of cloth, whereas if such inaccuracies were allowed in the closing of filled paper bags the defective and irregular stitching produced would not efficiently close the bag and would often result in breaking or jamming the mechanism. An object of our invention is to devise a machine sufficiently strong and rugged to operate on heavy filled paper bags.

A specific feature of our invention comprises a feed dog so mounted and operated as to have constant positive backing rather than the old style of mounting of the feed dog at the end of relatively long members. These long members could not stand the severe stresses without bending, and no operating mechanisms were found which could operate through short members due to the relative lack of space in the normal sewing head. Our invention is designed to overcome this problem.

A further object of our invention is to provide a feed dog which operates in a straight path during the feeding movement so that the stitches will have exactly the same length, an end which could not be attained in a sewing mechanism having a feed dog designed to operate in a rounded path during its feeding stroke since the smooth, hard surface of the paper would not allow such a feed dog to positively feed during the time when it was approaching and receding from the presser foot.

A further object of our invention is to provide a feed dog, having the foregoing characteristics and advantages, which approaches and recedes from the plane of the material in substantially a normal path thereto, and without lateral deviation from the line of stitching, thereby avoiding the gouging and marking of the material which unavoidably occurs in the use of feed dogs pivoted on relatively long structural members.

Such mechanism is especially adapted to be

employed in connection with driving mechanism comprising a main drive shaft extending parallel to the principal axis of the needle and having eccentric means mounted thereon for the purpose of driving the feeding mechanism as well as other moving parts of the machine, and the sewing machine of our invention is also especially adapted to be employed in conjunction with mechanisms for filling and closing open-mouth bags as those described and claimed in the co-pending application of Robert N. Cundall, Serial No. 640,758, filed Nov. 2, 1932, and the copending applications of Robert N. Cundall and Lincoln A. Cundall, Serial Nos. 666,114 and 686,816, filed April 19, 1933 and September 9, 1933, respectively.

With respect to this and other apparatus, it is desired to point out that, while the feeding mechanism is referred to herein as being for the purpose of advancing the material through the sewing machine, it is not absolutely essential that the actual forward motion of the material be caused by the feeding mechanism, as this motion may be effected by other means and the feeding mechanism may actually cause the sewing machine to travel along the paper, whether the latter is stationary or in motion. In any event, however, the function of the feeding mechanism is to assist in producing a relative movement of the material being sewn with respect to the sewing machine, and it is immaterial in so far as our present invention is concerned whether the one or the other is actually caused to move by the feeding mechanism.

Thus, in sewing the mouths of previously filled bags, especially bags adapted to contain large amounts of materials, it is not ordinarily feasible to move the bags along in an intermittent jerking movement, and the relatively stiff and rigid paper allows for no movement of the paper relative to the head while the needle is engaged with the paper during stitching.

As shown in the aforesaid co-pending applications of Robert N. Cundall and Lincoln A. Cundall, a sewing head for such use may be pivotally mounted on an axis normal to the plane of the material being sewn, the head being rocked about this axis as the paper advances, or as the head is moved along the paper, as the case may be.

Our invention is therefore especially adapted to be employed in a sewing head of this character, in which the various moving parts are driven from a main drive shaft having its axis parallel to that of the needle and having eccentric means for actuating the needle, the feeding mechanism and the looper mechanism. Such a head, when

employed for stitching the mouths of previously filled bags, and, it may be, for other purposes as well, is preferably pivotally mounted on an axis passing through the center of gravity of the head 5 or coaxial with the drive shaft, but in any event normal to the plane of the material being sewn.

More specifically, our invention contemplates, in addition to a feed dog mechanism mounted upon a shaft in the manner aforesaid extending 10 parallel to the direction of advancement of the material being sewn through the machine, the provision of means, actuated by an eccentric located upon or driven by the main drive shaft, for reciprocating the feed dog mechanism to and 15 fro along this shaft, that is to say, in the direction of motion of material being sewn and opposite thereto; and of means, also driven by an eccentric device mounted upon the main drive shaft or connected thereto, for contributing a 20 reciprocal movement to the feed dog mechanism about the principal axis of the aforesaid shaft extending parallel to the direction of the movement of the material being sewn, and whereby the feed dog proper is caused to advance through 25 the feed plate to grip the material and to be withdrawn therefrom. The latter means is furthermore so designed and constructed in accordance with our invention that the thrust exerted by the presser foot or the feasible biasing means 30 therefor, through the presser foot and the material being sewn upon the feed dog and tending to force the latter back through the feed plate, is resisted by structural members lying substantially or entirely in the line of thrust. In other 35 words, the feed dog is provided with a rigid metal backing located directly in the line of thrust exerted by the presser foot, as distinguished from prior devices in which this thrust was resisted by flexible means or by structural members extending 40 more or less laterally with respect to the line of thrust and supported at a point removed from the direct line of thrust.

Thus, in some prior devices of the general character recited hereinabove, the feed dog mechanism has been mounted at the end of a relatively 45 long structural member extending laterally with respect to the line of thrust of the presser foot and supported at some distance therefrom, and when such prior devices were adjusted to give a 50 sufficiently strong gripping of the material being sewn to take care of such stresses as are involved in sewing the mouths of large open-mouth filled paper bags or the like, such lateral members tended to yield or bend, thereby reducing the 55 grip of the feed dog or presser foot on the material being sewn or causing a misalignment of the material being sewn during the operation.

According to our invention, however, this disadvantage of prior devices is overcome by means 60 of the device herein set forth and the machine may be adjusted to grip the material being sewn very tightly without fear of bending or overstressing any structural parts thereof, or of injury to the mechanism, or of a tendency toward misalignment 65 of material being sewn as it is advanced through the machine.

In a more specific aspect, our invention contemplates the provision of a cam device, preferably a sliding cam, adapted to travel between the 70 feed dog mechanism and a fixed member, for example, the frame of the sewing machine itself, in such manner as to produce an oscillation or reciprocal motion of the feed-dog device about the shaft on which it is mounted, the insertion 75 or operation of the cam mechanism with respect

to the feed dog mechanism taking place substantially in the line of thrust exerted by the presser foot and providing structural means in which the thrust of the presser foot produces a compressive stress in the feed-dog backing means as distinguished from bending moment or shear.

In another more specific aspect our invention contemplates the provision in a sewing machine, of a single main driving shaft, a needle bar reciprocating in a line parallel to the main shaft, 10 a looper cooperating therewith to form stitches, a feed dog for advancing the material relatively to the needle, and eccentrics on the main shaft for operating the needle, the looper and the feed dog. The latter provision is a tremendous advance 15 in that it makes practical the extreme simplification and efficient operation of sewing machines designed for heavy duty. In this respect it is to be noted that there is a complete lack of rotating cams of any sort, such as have been found necessary in prior machines. Such cams, subject to terrific wear and stresses, required continual replacement due to the fact that a cam cannot be adjusted and once its correct contour is lost must be replaced. These cams were very expensive 20 due to the accuracy necessary and required the maintenance of expensive routing or special milling machines at the manufacturer's plant. With our invention each rotating driving element comprises a simple eccentric, easily turned out 25 on a lathe and easily adjustable to compensate for wear as is well known. Further, our invention comprises other simple parts in all respects, any of which may be economically and easily replaced.

In order that our invention may be more clearly set forth and understood, we now describe, with reference to the drawings accompanying and forming a part of this specification, an illustrative instance of the manner and form in which our invention may be embodied and utilized. In 40 these drawings:

Fig. 1 is an elevational view of a sewing machine constructed in accordance with our present invention, in which the sewing machine appears with the usual cover plate, as well as other parts having no bearing upon the present invention, removed for the sake of clarity to give a better view of the operating and structural parts of the machine.

Fig. 2 is a bottom view of the apparatus illustrated in Fig. 1;

Fig. 3 is an enlarged vertical sectional view of a portion of the apparatus illustrated in Fig. 1 taken on the line 3—3 of Fig. 1;

Fig. 4 is an enlarged vertical sectional view of the apparatus illustrated in Fig. 3 along the line 4—4 of Fig. 1;

Fig. 5 is an enlarged vertical sectional view similar to Fig. 1, but having parts of the casing broken away to allow a clear view of the feed dog, and the looper mechanism removed in part to allow a clear view of the feed dog operating means;

Fig. 6 is a schematic view of the path of travel of the feed dog, the line A—B representing the face plate of the machine, and the shaded portion representing the feeding stroke and illustrating the straight line characteristics thereof;

Fig. 7 is a similar schematic view representing the movement of the needle point normal to the material and illustrating its timed relation to the feed dog travel;

Fig. 8 is a similar schematic view representing the orbital path of movement of a point on the

looper in relation to the needle which reciprocates normal to the plane of Fig. 8;

Fig. 9 is a view similar to Fig. 6 but representing a feed dog path resulting from a simple variation which allows a shorter feeding stroke;

Fig. 10 is a view similar to Fig. 6 but representing a feed dog path resulting from a simple adjustment which also allows a shorter feeding stroke and hence allowing a relatively greater time for the needle and looper to operate; and

Fig. 11 is a cross section taken on line 11—11 of Figure 2 of the means to cause the feed dog to move vertically.

Similar reference numerals designate similar parts in each of the several views of the drawings.

Referring now to the drawings, there is illustrated a sewing machine or sewing head having a frame 1 of more or less conventional shape with a throat portion 2 through which the material to be sewn is advanced. The direction of advancement of material through the sewing head, as viewed in Fig. 1 is perpendicular to the plane of illustration and away from the observer. At one side of the throat portion 2 there is provided a feed plate 3 of conventional type having the usual openings (not shown) through which a feed dog member 4 is adapted to move.

Located in the entering portion of the throat portion 2, we provide a presser foot 5 of more or less conventional shape opposing and adjacent to the feed plate 3, and mounted upon a support indicated generally at 6 in such manner as to be adjustably spaced from the feed plate 3. The supporting means for the presser foot 5 indicated generally at 6 is constructed according to any well known manner to exert a flexible biasing force normal to the face of the feed plate 3. Thus the presser foot 5 may be adjusted to clear the feed plate 3 by a distance commensurate with the thickness of the material being sewn, while yieldably resisting further displacement from the feed plate 3 by a force commensurate with the extent to which the material being sewn must be gripped by the feed dog 4 and the presser foot 5 at each period of advancement. It will be understood that the required gripping force may vary considerably but that, in sewing the mouths of previously filled heavy paper bags of large capacity, this force will be far more severe than is required in machines to be employed for lighter duty as, for example, for the sewing of relatively small cloth bags. The specific mechanism for applying this yielding bias force to the presser foot 5 is similar in principle to that employed in previous machines and here need not be described in detail.

In the instance illustrated, the sewing machine 1 is provided with a main drive shaft 10 journaled in bearings 11 and 12 attached to or forming a part of the frame 1, which drive shaft 10 has a principal axis perpendicular to the plane of the material being sewn and is provided with driving pulleys 13 and 14 and a hand wheel 15, all of which are conventional in character and have no bearing upon the present invention except insofar as they typify means whereby the shaft 10 may be connected to a suitable driving motor (not shown). At one end of the shaft 10, there is provided an eccentric or crank member 16 which is operatively connected by means of a connecting rod 17 to a bell crank 18 pivotally mounted upon a pin 19 attached to the frame 1. The end of the bell crank 18 opposite to that 75 pivotally connected to the rod 17 is operatively

connected by means of a link or links 21 to a lug 22 mounted upon a needle holder bar 23 having a needle 24 and journaled in bearings 25 mounted upon and forming a part of the frame 1.

The principal axis of the needle bar 23 is normal to the face of the feed plate 3, that is to say, normal to the plane of the material being sewn, and parallel to the principal axis of shaft 10 and in each revolution of the shaft 10, the needle bar 23 is caused to move forward, thrusting the needle 10 through the material being sewn and the openings in the presser foot 5 and the feed plate 3 into the position in which it is illustrated in Figs. 1 and 2 and then to be withdrawn from the material being sewn in order to permit the material 15 to be moved ahead with respect to the needle by the feed dog 4 in a position for the next stitch.

The needle 24 is provided with the usual eye (not shown) through which passes the needle thread 30. The latter is supplied to the needle 24 from a suitable thread stand (not shown) through a thread tension device 31, a guide tube 32, an eye 33 mounted upon the rear end of the needle bar 23 and fixed eyes 34 conventionally located adjacent the bearings 25.

In the present instance, the reciprocation of the needle 24 carrying the thread 30 cooperates with a looper 35 carrying a second thread 36 to form a double-thread interlocked chain stitch. The looper 35 is fully illustrated except for its extreme tip in Fig. 1. For a better understanding of the looper and of the type of stitch formed by the machine reference may be made to the United States Patent of George Hoepner #1,270,948, issued July 2, 1918, wherein is illustrated and claimed a single form of the same general type of looper. The looper 35 is mounted in a holder arm 37 attached to one end of a rod 38 the other end of which is pivotally attached to an eccentric portion 39 of the main drive shaft 10. The rod 38 is slidably mounted in a sleeve member 40 pivotally mounted at 41 to the frame 1. A part of sleeve member 40 is removed in Fig. 5 for the sake of clarity.

It will be understood by those skilled in the art 45 and familiar with devices of this character that, as the shaft 10 rotates, the looper 35 is caused to travel in a closed and more or less narrow elliptical path lying in a plane parallel to the plane of the material being sewn, during the course of which path it passes downward on one side of the then retreating needle and enters a loop being formed in the needle thread 30, and subsequently rises on the other side of the path of the needle, producing a triangle of thread, one side of which is 50 formed by the aforesaid looper, another side by the looper thread 36, and the third by the aforementioned loop, which triangle is entered by the needle on its next forward motion. Shortly thereafter, the loop is stripped from the rising looper, 55 thereby producing an interlocking of the needle thread 30 and the looper thread 36 on one side of the material being sewn.

Our improved mechanism for feeding the material to be sewn through the machine, or for advancing the sewing machine relative to the material being sewn, as the case may be, between the stitching intervals, is best illustrated in Figs. 3, 4 and 5 to which reference will now be had. The feed dog 4, as mentioned hereinabove, is required 65 to periodically advance through the throat plate 3 to grip the material against the biased presser foot 5, then to move forward in the direction of movement of the material being sewn relative to the sewing machine while gripping the material, 70 75

then to be retracted out of engagement of the material being sewn through the throat plate 3 and finally to move back in a direction opposite to the direction of the material being sewn with respect to the sewing machine in order to complete its cycle and to be ready to be again advanced to grip and move the material being sewn.

In order to provide for this motion of the feed dog 4 and to insure that the forward motion of the feed dog, while in engagement with the material being sewn, will be in a substantially straight line rather than in a curved or arcuate line, the feed dog 4 is mounted upon an arm or feed dog holder 50, the opposite end of which terminates 10 in a sleeve 51 mounted upon a pin 52 secured to the frame 1 at a suitable distance from the throat plate 3 and extending parallel to the stitching line, that is to say, parallel to the direction of movement of material being sewn with respect to the 15 sewing machine. The sleeve 51 is so mounted upon the pin 52 as to be capable of a sliding movement along the pin 52 or a rocking movement about the latter. The pin 52 may be provided with an enlarged head 53 to limit the movement of the sleeve 51 along the same. In order to provide for the forward and backward sliding movement of the sleeve 51 along the pin 52, the arm 50 is provided with a stud 54 which is adapted to be received into and freely held by the bifurcated end, or, preferably, within an oval hole through a member 55 mounted in the end, of a 20 rocking lever 56 pivotally mounted at 57 on a supporting member 58 attached to the frame 1 and having at its opposite end a yoke 61 adapted to receive an eccentric 62. The eccentric 62 is 25 mounted upon the main drive shaft 10, and as the shaft 10 rotates the eccentric 62 swings the rocking lever 56 to and fro about the pivot 57 and through the stud 54 causes the arm 50 to 30 slide to and fro along the pin 52.

The manner in which the stud 54 connects arm 50 to lever 56 is such that the arm 50 is free to rock slightly about the pin 52 without interfering with the motion imparted by the rocking lever 56 and the eccentric 62.

We further provide a spring or springs 63 lying between the arm 50 and the rocking arm 56, which springs 63 exert a biasing force tending to rock the arm 50 about the pin 52 in a counter-clockwise direction as viewed in Fig. 5 and thus keeps the feed dog 4 retracted out of engagement with the material being sewn and member 64 against cam member 65 as will appear hereafter.

In order to provide for advancing and retracting the feed dog 4 through the openings in the throat plate 3, the arm 50 is provided with a rearwardly extending member 64 preferably connected to the arm 50 immediately behind and adjacent to that point at which the material receives the thrust of presser foot 5. It will be obvious, however, that the member 64 may readily be attached to the feed dog 4 if so desired but, in any event, the member 64 is preferably so situated as to be directly aligned with the force exerted by the flexibly biased presser foot 5 when the feed dog 4 is in its advanced position in engagement with the presser foot 5 or the material being sewn.

Lying immediately behind the member 64 and limiting rearward motion of the member 64 and the feed dog 4 under the influence of the spring 63 we provide a sliding cam member 65, the rear face of which opposite the member 64 is provided with an inclined salient cam portion 66 which lies adjacent to and, upon vertical reciprocation of the member 65 is adapted periodically to engage

and ride over an inclined salient cam portion 67 of a fixed cam member 68 which may conveniently be attached to the frame 1. Preferably, the inclined cam portion 67 is provided on a separable and adjustably mounted part 69 which is simple to make and negligible in cost. It will be obvious that, upon vertical downward movement of cam member 65, cam surfaces 66 and 67 will slide past each other and cause a resultant horizontal movement of the cam member, thereby causing the feed dog to move outwardly. This motion of the feed dog is accomplished through transmission of the outward thrust by member 64 to cause the swinging of arm 50 about pin 52. Upon upward movement of cam member 65, the cam surfaces 15 will disengage and the feed dog will be retracted due to the thrust of the presser foot, this motion being furthered by springs 63 to insure complete retraction of the feed dog below the surface of throat plate 3. Cam member 65 is guided in its 20 reciprocatory movements between the frame 1 and a flange 70 on member 68.

In order to provide for vertically reciprocating the member 65 in such timed relation with respect to the oscillation of the rocking member 56 as 25 to alternate the periods of maximum rates of advancement and retraction, respectively, of the feed dog 4 through the throat plate 3 with the forward and backward motions, respectively, of the feed dog 4 in and against the direction of 30 movement of the material being sewn, the member 65 is preferably actuated by some form of eccentric mounted upon the shaft 10 and having a predetermined angular position with respect to the eccentric 62 and the rotation of the shaft 10. 35 While a separate eccentric may be employed for this purpose or the vertical reciprocation of the cam member 65 may be derived from the eccentric 62 itself, in the present instance we have illustrated a convenient and space-saving mechanism 40 for effecting the vertical reciprocation of the member 65.

In this instance, the upper portion of the member 65 is pivotally connected by means of a connecting rod 71 to a knuckle member 72 mounted 45 upon the connecting rod 38 which actuates the looper 35 and, as the shaft 10 rotates, the knuckle 72 through the connecting rod 71 causes the member 65 to slide up and down thus alternately advancing and retracting the feed dog 4 through 50 the openings in the throat plate 3 in the manner set forth hereinabove.

Knuckle 72 has an orbital movement in the plane of Fig. 4 and member 65 has a straight line movement in this plane, while knuckle 72 has 55 straight line movement in the plane of Fig. 5 and joint 73 has an orbital component of movement in this plane due to the coaction of cam surfaces 66 and 67. Therefore, the joints at 72 and 73 each comprises a universal joint to an extent 60 sufficient to allow for such movements.

It will be obvious from inspection of the drawings and more particularly Fig. 5, that the force exerted by the presser foot against the feed dog 4 when the latter is advanced through the throat 65 plate 3 is resisted by the compressive strength of the members 64, 65 and 68 and that the stress thus set up is substantially directly in alignment with the direction of the force exerted by the presser foot 5. Due to the fact that the stress 70 thus set up is resisted substantially entirely in compression and bending or shear stress is substantially and entirely avoided, it is possible to construct the various parts receiving the stress much more lightly with respect to a given force 75

exerted by the presser-foot mechanism than would otherwise be true, and, consequently, it is possible according to our invention to greatly reduce the inertia and weight of the feed-dog actuating mechanism as compared with prior devices. This is especially important with respect to such relatively heavy presser foot action as is required to grip materials such as paper and more particularly the mouths of heavy paper bags.

10 Figs. 6, 7 and 8 are motion studies of the various operating parts of our sewing machine, which taken in connection with Figs. 3, 4 and 5 will explain the operation thereof. Figs. 4 and 5 are views taken at what may be termed the beginning 15 of a working cycle, or 0° of rotation of shaft 19. Accordingly, Fig. 3 is taken at 90° of rotation. It is apparent that as shaft 19 rotates 90° from the position of Fig. 5 to the position of Fig. 3, member 50 will move to the right approximately one 20 half of its travel, while cam member 65 moves downward in a straight line as cam surfaces 66 and 67 approach each other. As a result the feed dog will have a straight line movement to the right (Fig. 6). During this time looper 35 25 (Fig. 8) descends approximately one half of its travel while swinging to the left of the needle 24 which is then moving outward (Fig. 7). During the next 30° of rotation cam surface 66 rides up on cam surface 67 while member 50 starts toward the left, causing the feed dog to be thrust 30 forward along a curved path to engage the material. Simultaneously needle 24 clears the material. During the next 60° of rotation cam plate 35 35 is traveling downward in a straight line while member 50 continues to move toward the left in a straight line, the feed dog gripping the material and feeding it through the machine. Simultaneously therewith, looper 35 travels to its lowest point while swinging back toward the right, but 40 being still to the left of a vertical plane through the needle line and below the needle. The next 60° of rotation causes the feed dog to complete its working stroke, and during the next 30° of rotation to retract as cam surface 66 slides off of 45 cam surface 67. During this latter 90° of rotation the looper 35 travels upward while swinging to the right of the needle, and during the last 30° thereof the needle penetrates the material. The final 90° of rotation causes the feed dog to 50 return in a straight line to its initial position, while the looper completes its orbital movement and the needle fully penetrates.

It is obvious from the foregoing that slight variations in the angularity of eccentrics will 55 cause variations in the path relationship of the various parts. Also, a vertical adjustment of member 69 may be utilized to create a longer or shorter working stroke of the feed dog. It is equally apparent that by changing the slope of 60 the cam surfaces 66 and 67 a quicker or slower outward movement of the feed dog may be realized. For example, in Fig. 9, the angle of slope of the cam surfaces has been materially lessened so that 60° of rotation is required to cause them 65 to pass each other, resulting in a short feeding stroke lasting only 60° of rotation and allowing a greater proportionate period for the needle to remain retracted in the material. In Fig. 10, the member 69 has not been altered but has been 70 lowered so that the feed dog remains for 10° more than in Fig. 6 before starting outward. This results in a working stroke lasting only 100° , as compared to 120° in Fig. 6. Many other possible relationships may be evolved to meet immediate 75 demands. However, the characteristics of the

machine outlined in Figs. 6, 7 and 8, have been found satisfactory and permissive of the following desirable features of operation, i. e., due to the fact that the feed dog is operative only during 120° of rotation, the needle and looper are allowed 5 240° in which to form the interlocked chain stitch. Obviously this allows a substantially greater number of stitches per minute and a correspondingly higher output of bags.

In the foregoing, it is made clear that the feed 10 dog is imparted a straight working stroke shorter than the full reciprocation of member 50 along pin 52 and during less than 180° of rotation of the shaft, or less than π radians. This allows 15 a greater proportionate period for the needle and looper to cooperatively interlock the threads and hence a greater number of stitches per minute. It is also clear that by adjustment of member 69, the operative angle of rotation is lessened commensurately with lessening of the straight line 20 working stroke, so that adjustments in the length of stitch is made possible.

Another feature of our invention is that the feed dog is mounted on member 50 swinging about and slidably on pin 52. Thus the feed dog 25 is rockably mounted on an axis of rotation parallel to the plane of the material. The same effect would be obtained if the member 50 were formed with pintles rotatably and slidably guided in holes in the walls of the frame 4, the important thing being that at the axis of the member 52, or its equivalent, the feed dog holder may be considered as being displaceable only in the line of the axis, while the opposite end of the holder and the feed dog are displaceable in two 30 directions resolved into a closed path of definite form and dimensions. The feed dog has only a negligible outward swing from the moment it contacts the material until it reaches its full outward position, and the lift of the feed dog 40 due to its swinging movement is infinitesimal. The feed dog therefore may be considered as having a practically straight outward thrust and does not draw across and chew the material as was the case in the old machines having feed 45 dogs mounted on long members swinging about a distant pivot. In other words, the feed dog while in contact with the material does not have any motion or lateral displacement up or down from the line of stitching.

As previously pointed out it is immaterial to the 50 operation of our device whether the material is drawn through the machine or the machine drawn past the material as set forth in the aforementioned applications of Lincoln A. Cundall 55 and Robert N. Cundall. The foregoing description sets forth a stationary machine in which the feed dog 4 actually forces the material forward during the time the needle is withdrawn. However, our invention makes practical the use 60 of continuous feeding of filled bags by causing the feed dog to positively grip the material and swing the sewing head back after having been rocked forward by the engagement of the needle therewith, or the use of a sewing head which 65 travels past a stationary bag by causing the feed dog to positively grip the material and pull the sewing head relatively thereto while the needle is disengaged.

It will be obvious to those skilled in the art 70 that while we have shown a preferred form of mechanism whereby this result may be achieved, our invention is not limited in its broadest aspect to such specific embodiment but may variously be embodied within the scope of our invention, and 75

other specific feed mechanisms of the general character recited hereinabove may be employed. Thus, various types of cams may be substituted for the specific cam mechanism 65 and 68 described and illustrated herein without departing from the scope of our invention.

It will further be obvious to those skilled in the art that our invention possesses important advantages with respect to the operation and construction of sewing machines, more especially sewing machines intended for heavy duty work, more particularly the stitching of heavy and relatively stiff materials such as paper, cardboard, or the like, these advantages in part consisting of improvements in the motion characteristics of the mechanism as well as the structure of the mechanism itself.

As pointed out hereinabove, our invention is not limited to the particular exemplification given hereinabove but may variously be embodied and utilized within the scope of the claims herein-after made.

We claim:

1. In a sewing machine, a feed dog for advancing the material to be sewn in a series of intermittent movements relative to said machine, a holder, upon which said feed dog is mounted, adapted to be reciprocated along a fixed axis extending parallel to the direction of movement of the material relative to the sewing machine, and a fixed pin pivotally supporting said holder and constituting said axis, said holder having a length from said axis to said feed dog at least several times the length of the arc of movement of said feed dog about said axis.

2. In a sewing machine, a feed dog for advancing the material to be sewn in a series of intermittent movements relative to said machine, a

holder, upon which said feed dog is mounted, adapted to be reciprocated along a fixed axis extending parallel to the direction of movement of said material relative to the sewing machine, a fixed pin pivotally supporting said holder and constituting said axis, and means for rocking said feed dog about said axis toward and away from the material, said holder having a length from said axis to said feed dog at least several times the length of the arc of movement of said feed dog when rocked by said means.

3. In a sewing machine, a throat plate having openings therein, a presser foot located adjacent to said throat plate and flexibly biased toward said throat plate, a feed dog adapted to be advanced through the openings in said throat plate to grip the material being sewn against said presser foot and to be withdrawn through said openings and out of engagement with said material, a holder upon which said feed dog is mounted, a pin having its principal axis located in a plane parallel to the face of said throat plate and pivotally supporting said holder, said holder having a length from said axis to said feed dog at least several times the length of the arc of movement of said feed dog to engage the material, means for rocking said holder about said pin to advance and retract said feed dog through said throat plate, said means comprising members located substantially in line with said feed dog and said presser foot and constituting a rigid backing for said feed dog, and means to move said holder along said pin to cause said feed dog to advance the material engaged thereby with respect to said throat plate.
